UNITED STATES PATENT OFFICE.

EDUARD LANKES AND KARL SCHWÄRZLER, OF MUNICH, GERMANY.

PROCESS OF PREPARING PRINTERS' OVERLAYS AND UNDERLAYS.

No. 892,166.

Specification of Letters Patent.

Patented June 30, 1908.

Application filed August 2, 1906. Serial No. 328,953.

To all whom it may concern:

Be it known that we, EDUARD LANKES and KARL SCHWÄRZLER, subjects of the King of Bavaria and the Emperor of Austria-Hungary, respectively, residing at Munich, Germany, have invented certain new and useful Improvements in Processes of Preparing Printers' Overlays and Underlays; and we do hereby declare the following to be a full, clear, and exact description of the invention, such as will enable others skilled in the art to which it appertains to make and use the same.

The present invention relates to an improved process for the production of relief underlays and overlays from a suitable surface capable of being etched, and specifically, from a chalk mass or the like, upon an underlayer of paper material. The reliefs are produced by etching and may be employed in the printing press as an underlay for the printing plate, but generally, however, as an overlay upon the pressure cylinder or tympan sheet in order to regulate the pressure of the press to emphasize the gradations of tone in the picture, and to protect the fine parts of the printing plate so as to insure a great number of impressions before wearing it out.

Since, in the carrying out of the known etching processes, the depth of stratum removed in places by etching and also the differences of the reliefs and the printing effect depend as well upon the shorter or longer time of etching as also upon the strength of the etching solution and, further, upon the more or less vigorous movement during the etching and the flowing of the etching bath, therefore, it has been difficult or impossible to produce with safety a determined height of the relief or to etch several reliefs of the same height. This evil becomes especially disadvantageous when several such consequently high reliefs are to be used as underlays or overlays at the same time in one press, in which case they must first, by a tedious leveling process be brought to an equal height for printing.

The present improved process has for its further object, therefore, to provide a means by which the depth of the etching and therefore the height of the relief can be gaged exactly, during the etching, so that it is easy, by interrupting the etching process at the right time, to obtain reliefs of exactly equal heights. This is obtained by the following arrangements of the coatings of the relief mass to be etched upon the base. The

stratum to be etched is coated in a uniform thickness upon a differently colored base or upon a base whose upper surface only is differently colored, as for example, a white stratum upon a base colored red, or reversely. As an alternative, the etching ground itself is coated upon the base in several thin strata of different colors. As an etching ground one may employ for example, chalk, lime in combination with a binding matter, as a base, paper material. However, there may also be employed as an etching ground other mineral material capable of being attacked by acid, in combination with a binding material. For chalk, a solution of chlorid of lime is very suitable as an etching means.

The coating of the etching strata and the working out of the relief can be done either upon one side of the paper base, or, also, for the purpose of increasing the action, upon both sides at the same time. In the second case, the printing plate or electrotype in connection with which the relief is to be employed as an underlay or overlay is placed in a printing press, and upon a tympan sheet fastened upon the printing cylinder of the press, the illustration is printed several times one over the other, exactly registering, after an inking each time with a resist ink. The printing plate is again freshly inked, the paper sheet, provided on both sides with an etching ground, is laid upon the freshly printed tympan sheet and run through the press under pressure, whereby there is obtained an impression from the printing plate upon the front of the etching ground and upon the back a negative impression, due to the taking up of the excess of ink on the tympan sheet, exactly registering with the impression on the front etching ground. Immediately after the resulting printing of the picture, while the resist ink is yet moist, or also, however, at a later time when the colors are completely dry, the paper sheet provided on both sides with a printed etching ground can be placed in a 2% etching bath, which consists of water with the addition of dissolved chlorid of lime, in order to develop the relief.

The etching bath which is kept in motion continuously in order that the front and rear sides of the printed plate shall be simultaneously attacked is allowed to act only until at the bright places or at the unprinted margin at the outer border of the picture, the upper

stratum is etched away and the differently colored stratum under it or the paper base itself appears. Owing to the translucent properties of the sheet and the tinting of the 5 strata, the progress of the etching may be advantageously observed by transmitted light as in the development of a negative in the photographic dark room.

The darker portions of the picture, remain 10 untouched by the etching fluid because they are protected by the resist ink while the half tones are deepened more or less corresponding to their tone values, and the high lights are etched through to the under layer where 15 by the appearance of the differently colored underlayer is a sure guide for the termination of the etching. After the completion of the etching, the relief is washed in water, the most of the water removed between absorb- 20 ent paper and the complete drying accomplished in the open air, whereupon the relief is finished. As an overlay, the relief so prepared is placed upon the tympan sheet directly over the printed impression thereon, 25 taking care that every detail of the relief shall be in exact register with the same detail of the printed impression and, consequently be exactly opposed to the same details of the printing plate. The positioning of the relief 30 overlay is greatly facilitated by the inherent semi-transparent qualities of the paper base and chalk relief portions, by means of which the relative positions of the overlay and impression can be visually ascertained. The 35 transparency of the overlay can be further enhanced by oiling. As an underlay the relief sheet is placed beneath the thin printing plate or electrotype, between the same and the block on which it is mounted, corre- 40 spondence being secured by cutting the two to conform or providing guide lines or points to secure exact register. When used as an underlay, the thin printing plate will be firmly backed up in the darker printing por- 45 tions by the relief portions of the underlay while the high lights will have a space at the rear where the upper surface of the underlay is etched away, and as a consequence the differences in tone of the printed picture will 50 be emphasized in printing. The same result is secured as an overlay, the relief portions sustaining the paper on which the printing is being done against the pressure of the darker portions of the printing plate, while the 55 deeper portions of the overlay permit the paper to yield at the high lights, and in the half tones in proportion. Not only is a more vivid and clear impression thus secured but the life of the printing plate is prolonged 60 as the more delicate portions and details of the picture are protected. The chalk relief sheet has further artistic value in itself, as the paper base and chalk strata etched to varying degrees of thickness and so placed 65 that a strong light shall pass therethrough,

constitute a beautiful translucent picture in which all the details and tones of the typographic print are brought out, not by the use of ink but solely by the differences in amount of light permitted to pass through 70 the varying thicknesses of the picture. The use of differently tinted strata in the etching ground, moreover, tints the picture, when viewed as a transparency, more or less, as the stratum is etched away to a greater or less 75 extent.

Having thus described our invention, what we claim as new is:

1. An improved method of preparing reliefs, which consists in printing with a resist 80 ink upon a sheet of etchable material consisting of differently tinted homogeneous strata, and etching the surface of the sheet until an underlying stratum appears.

2. An improved method of preparing 85 printers' relief underlays and overlays, which consists in taking an impression from the printing plate upon a sheet of chalk material consisting of differently colored strata by means of a resist ink, etching the sheet, and 90 placing the etched relief in register with the printing plate.

3. An improved method of preparing printers' relief underlays and overlays, which consists in taking an impression from the 95 printing plate upon a sheet of etchable material consisting of differently colored strata by means of a resist ink, etching the sheet until an underlying stratum appears, and then placing the etched relief in register with 100 the printing plate.

4. An improved method of preparing printers' relief underlays and overlays, which consists in taking an impression from the printing plate upon a sheet of paper having 105 an etchable surface consisting of a differently colored stratum by means of a resist ink, etching until an underlying stratum appears and then placing the etched relief in register with the printing plate.

5. An improved method of preparing printers' relief underlays and overlays, which consists in printing heavily by means of the printing plate and a resist ink upon the tympan sheet, laying over the heavily inked 115 impression a sheet of etchable material consisting of differently colored strata, operating the press to obtain an impression from the plate upon the face of the etchable sheet and from the tympan sheet upon the back of the 120 etchable sheet, etching the sheet and placing the etched relief sheet in register with the printing plate.

6. An improved method of preparing printers' relief underlays and overlays, which 125 consists in printing heavily by means of the printing plate and a resist ink upon the tympan sheet, laying over the thus heavily inked impression a sheet of etchable material consisting of differently colored strata, op- 130

erating the press to obtain an impression from the plate upon the face of the etchable sheet and from the tympan sheet upon the back of the etchable sheet, etching the sheet 5 until an underlying stratum appears, and again positioning the etched relief sheet in contact with the tympan sheet in exact register with the impression thereon and in opposition to the printing plate.

10 7. An improved method of preparing printers' relief underlays and overlays, which consists in printing heavily by means of the printing plate and a resist ink upon the tympan sheet, laying over the thus heavily 15 inked impression a sheet of etchable material consisting of a paper base with differently colored superposed chalk strata, operating the press to obtain an impression from the plate upon the face of the etchable sheet and 20 from the tympan sheet upon the back of

the etchable sheet, etching the sheet until an underlying stratum appears, and again positioning the etched relief sheet in contact with the tympan sheet and in exact register with the impression thereon and in opposition to the printing plate. 25

8. A sheet of translucent material composed of differently tinted strata bearing an etched representation, the deeper incut portions and the higher relief portions corresponding respectively to the lights and shadows represented. 30

In testimony whereof we hereunto affix our signatures in the presence of two witnesses.
